The ornamental design for a biopsy device, as shown and described.

DESCRIPTION

FIG. 1 is a perspective view of a biopsy device showing my new design;

FIG. 2 is a top view of the biopsy device of FIG. 1;

FIG. 3 is a bottom view of the biopsy device of FIG. 1;

FIG. 4 is a right side view of the biopsy device of FIG. 1;

FIG. 5 is a left side view of the biopsy device of FIG. 1;

FIG. 6 is an end view of the biopsy device of FIG. 1 as viewed from the distal end of the biopsy device; and,

FIG. 7 is an end view of the biopsy device of FIG. 1 as viewed from the proximal end of the biopsy device.

In the drawings, the broken lines depict unclaimed subject matter only and form no part of the claimed design.
